Straight Knitting Mach.

No. 9,037.

Patented Mar. 29, 1853.

UNITED STATES PATENT OFFICE.

JOHN MAXWELL, OF GALESVILLE, NEW YORK.

KNITTING-MACHINE.

Specification of Letters Patent No. 9,637, dated March 29, 1853.

To all whom it may concern:

Be it known that I, JOHN MAXWELL, of Galesville, Washington county, State of New York, have invented new and important Mechanical Movements in the Construction of Knitting-Looms; and I declare the following specification, with the drawings thereto attached as part of the same, to be a full and perfect description thereof.

10 Figure 1 represents a perspective view of a knitting loom of a usual form and arrangement exhibiting principally the arrangements of machinery in the front part of the loom. Fig. 2 represents, in elevation, 15 a portion of the machinery as seen in the rear of the loom.

In both figures similar letters indicate the same parts of the machine.

In Fig. 1 A A A A represents the stand 20 or frame of the loom; which is in its general arrangements similar to the ordinary knitting looms as now used in factories. B, B is the frame (commonly called the comb-bar), that carries the jacks C, C, and 25 the jack sinkers; D, D, the bar (called the lead sinkers bar,) that carries the lead sinkers; E the lead; G the jack and lead sinkers alternating with each other. The bar D, D, is attached at each end to the arms 30 J, J, by which it is connected with the sinker levers K above, and throw-out bars L below.

M is the needle bar; N the needles, lying 35 horizontally between M and a smaller upper bar O, called the falling bar, upon which the jacks rest.

P is the locking bar; R the thread carrier; H the presser attached to the lever S, S, by 40 which it is raised off and lowered upon the needles. The levers K and S, and the throwout bar L are operated by cams attached to the side faces of the wheels W, W, the wheels themselves being operated directly from the prime movers of the factory; T, T, standards on which K and S are pivoted; U, U, upright arms from the back ends of K and S with rollers in their lower extremities to receive the impulse of the cams on the wheels; X X springs attached 45 to the different levers to maintain them in place, except when moved by the cams; k, k, an upright gallows frame attached to the comb-bar B. On the back of its upper limb is a bar m of wood or other material from 50 which depend a set of small springs s, s, s, which press against the tail ends of the jacks

to keep them steady when freed from the pressure of the bar P.

t is a trip or upright knob called the slur-steeple attached to a sliding carriage Y, 60 called the slur, which lies within the frame B, and which can be moved backward and forward under the jacks to force their back ends upward during certain parts of the knitting process. The carriage Y slides 65 upon a slender vertical bar or rod z, called the slur bar, lying within the sides of the frame B, as shown in the drawing at Fig. 1.

My improved movements have reference first to the arrangements of the spring locking apparatus or that by which the motion of the bar P is duly regulated in reference to the jacks C, C, so as to hold them down, one end of them lying under the bar D and the other under bar P during certain parts 75 of the knitting operation.

It must be noted that in the ordinary knitting loom, the comb-bar B, B, has a small horizontal motion back and forth, in order to carry the sinkers along the needles 80 N in making the stitch, which motion is given by the levers L, which being forced in and out by the cams a on the wheels W, vibrate the arms J and through the connection of the half jacks (so called) b, b, which 85 are pivoted to cheeks c, c, on the comb-bar B and to bar D at the points d, d, give a slight reciprocating motion to the frame.

My locking apparatus, consists in the erection of two standards e, e, upon the back 90 ends of the half jacks b, b, these standards rising high enough to carry between their upper bent ends, and the bar P, springs f, f, strong enough to keep the bar firmly down upon the tail-ends of the jacks. Through 95 the springs, rods pass riveted to the bar, and passing through orifices in the upper ends of the standards, in order to steady the motions of the bar P. This placing of the standards upon the half jacks is important 100 inasmuch as it preserves the equidistance between the locking bar and the sinker bar during the evolutions of the machine. The pressure of the bar P upon the sinker bar is released at the proper time by the operation 105 of the cams g upon the levers Y. (In the drawing it being impossible to show the cam near the front wheel, or the lever on which the cam near the back wheel acts, it will be understood that the front wheel has behind it on its axis a cam like g, and that the cam g operates upon a lever like Y.)

- The lever Y is pivoted at p, so that when its back end is depressed, the front end rises against a vertical rod h which is screwed into the end of P, and thus raises the bar. 5 The height to which P is to be raised is adjusted by screwing the rod up or down through P, which permits the end of Y to make a greater or less sweep before it touches and lifts h.
- 10 The employment of the springs f, f, is of great service in a case of any derangement to the machinery, by which the steeple-slur (hereafter referred to) should be left under the jacks instead of passing entirely through 15 its whole course; the elasticity of the springs preventing injury to the machine, by relieving the jacks from the pressure of the locking-bar.
- Fig. 2 shows an elevation of so much of 20 the back view of the machinery as, in connection with Fig. 1, will exhibit these movements. k, k, shows the gallows frame with its springs s, s, s. The slur steeple as it lies behind the plate C² cannot be shown, but 25 the sliding carriage to which it is attached Y, has ears which are seen at v, v, on this side of the slur bar on which it slides. There are corresponding ears on the other side of the bar and a pin passes through the opposite ears. The thread carrier R is attached 30 at its bottom to a sliding bar w, which runs on the pins that pass through the said ears, by means of a slot in the bar, shown by a dark shading in the drawing. In the ordinary 35 machines the driving backward and forward of this bar is done by a complicated gearing. My method of doing it is as follows: A wheel A² is placed under the bar w coincident in its plane of motion. Straps 40 3, 3, on its periphery (crossing each other) are attached to the ends of the bar w, so that when the wheel makes a partial revolution to the right or left, the straps operating tangentially give an easy vibration to the bar. 45 On the axis of this wheel are fixed cams 4, 4, opposite to each other, and similar in form. Opposite or nearly opposite the center of this wheel A² a horizontal shaft B², parallel with the shaft of the wheels W, carries a 50 wheel Z, which gears in a pinion O of one-fourth its diameter placed on the shaft of wheels W, so that one revolution of the said wheels W shall produce one-quarter revolution of Z and its shaft. On shaft B² are 55 fixed four arms 5, 6, 7, 8—5 and 6 being in

line with each other, and 7 and 8 being also in a line with each other, but at right angles with 5 and 6. These arms are arranged to touch the cam 4, 4, as they pass around and thereby turn the wheel A² sufficiently to 60 move the sliding bar w the proper distance for its due operation. It is manifest that as these arms reach the cams in succession they will throw the wheel alternately to the right and left hand at each revolution of the 65 wheels W, to which wheels are affixed the cams which operate all the other movements of the loom, and give to each part its due motion. This is shown in Fig. 1 where on the wheels W, W the cams are shown as operating against arms having a roller set in the impinging arms thereof, the roller being kept with a due pressure against the cams by the springs X, X, which are seen in connection with the arms. 75

In the movement of the ordinary knitting looms, in order to bring the cloth over the new made stitch, the sinkers are brought forward together, and this bringing forward is done in two motions, by the first of which 80 the cloth is carried to the edge of the needles, and by the second is carried over the needles. These two motions are effected by two steps in the cam a very close to each other, with a depression between them so that the lever L 85 is shifted back and forth with a sudden jerk so violent as to require levers, arms, &c., of great strength to endure the work, and thereby limits materially the speed of the machine. 90

The movement in my looms is done by a single step or rise in the cam, as shown in the drawing on wheel W, (Fig. 1,) where the cam is represented in the act of making the throw out motion. 95

I claim—

The construction of the locking apparatus, by placing standards upon the back ends of the half-jacks to carry springs which regulate the pressure of the bar upon the jacks, 100 in combination with an apparatus for raising said locking bar, the whole constructed and arranged for the purpose and in the manner substantially as set forth in the within specification.

JOHN MAXWELL.
